[57] ABSTRACT

The invention concerns a quick closing valve, in particular a disc valve for antiskid devices on street vehicles with a closing member controlling a flow of pressure medium from a chamber of higher pressure to a chamber of lower pressure.

9 Claims, 3 Drawing Figures

FIG. 1

FIG. 3

WHEEL SLIP CONTROL APPARATUS HAVING QUICK CLOSING VALVES

BACKGROUND OF THE INVENTION

High requirements are frequently imposed on valves of this type with respect to the shortest possible closing time. This feature previously has been achieved by reducing the mass of the moving parts of the valve and by pre-unloading the closing member using a spring or a static pressure. However, these measures are unsatisfactory for achieving extremely short closing times such as are necessary, for instance, on nonskid devices of street vehicles.

The invention has the purpose of creating a valve of the type named that can be moved to its closed position as rapidly as possible and is distinguished by simple construction and a reliable mode of operation.

SUMMARY OF THE INVENTION

This task is solved according to the invention by the fact that the quick closing valve display means installed in the path of flow of the pressure medium for producing a reduction of the fluid pressure force acting on one side of the closing member to thereby increase the effectiveness of the fluid pressure force acting on the other side which force acts in the closing direction.

In this way it is possible to achieve an effective unloading of the closing member in the closing direction and thus obtain a considerable shortening of the closing time with the aid of devices automatically operative when the valve is to be closed which do not influence the mass of the moving valve parts or to only an insignificant degree.

In a further design according to the invention, the means for producing a reduction of the fluid pressure force on the one side are designed as a flow-deflecting body which is carried by the closing member, and installed at a distance from the closing member in such a way that the reduction in force produced is dependent on the velocity of flow. This reduction of force is effective to cause snap-acting movement of the closing member in the closing direction. Preferably, the flow-deflecting body is formed by a funnel-shaped piece tapering in the closing direction of the valve.

It is advantageous if the closing member that constitutes a valve has formed integral with one side thereof a coaxial concave dished conical surface which is tapered in the direction of a valve seat and therefore is curved in such a way that when the valve is open, the flow of pressure medium against the concave dished conical surface causes the direction of flow to be turned while maintaining a roughly constant effective cross section area of flow or one which increases in the closing direction. In this way, the flow of the pressure medium from the intake chamber to the outlet boring is unhindered and its direction of flow turned without special space-consuming separate turning means.

The means for producing a reduction of the fluid pressure force as the result of flow can also be formed according to the invention as an impingement body rigidly attached to the closing member and spaced a distance from it so that this body is immersed in the flow of the pressure medium. Advisably, the impingement body is a circular plate installed coaxially with the closing member and spaced a chosen distance from it.

It is further provided according to the invention that in the case of a pressure-medium activated quick closing valve whose activating member has one side acted on by the pressure in the higher pressure chamber, the means for producing the reduction of the fluid pressure force on the other side is formed by a throttle or choke installed between the higher pressure chamber on the one side and a valve intake chamber on the other side and bordered by the closing member. Thus, the activating member on its one side is capable of being acted on by the pressure in front of the throttle and on its opposite side by the pressure in the valve intake chamber which pressure is that behind or on the outlet side of the throttle.

It is possible within the limits of the invention to use the means for producing a flow-dependent pressure force according to the design discussed above either individually or in combination.

In order further to shorten the closing time of the valves of the pressure-medium activated quick closing valves, in another embodiment of the invention, it is provided that the closing member serves simultaneously as the activating member, whereby the closing and activating member is advisably formed by a membrane or diaphragm formed of an elastic material.

A further shortening of the closing times can be achieved by having the membrane supported on its activation side against a roughly cone-shaped housing seat in such a way that the membrane displays an increasing effective area as it is moved away from the housing seat during an activation stroke.

In the following, various examples of the invention are more closely explained with reference to the drawings.

FIG. 1 shows an antiskid device for street vehicles with a braking pressure control valve arrangement consisting of a supply valve and a release valve, partially depicted by diagram.

FIG. 2 shows a time-pressure diagram for the antiskid device according to FIG. 1.

FIG. 3 shows another variant or a second embodiment of the supply valve for the antiskid device according to FIG. 1.

The antiskid device shown in FIG. 1 displays a braking pressure control valve device 1 composed of a supply valve 2 and a release valve 3.

The supply valve 2 is installed in a pipe 6, 7, 8 leading from a compressed air container or reservoir 4 to a brake cylinder 5. The supply valve 2 has a brake valve 9 connected in front of it.

The release valve 3 is installed in a pipe 10, 11 leading from brake cylinder 5 to atmosphere.

Both valves 2 and 3 are designed as pressure-medium activated diaphragm-type valves and can be opened and closed by operation of magnetic valves 12 and 13. The magnetic valves 12 and 13 are operated by solenoids. The exciter circuits of the coils of these solenoids are connected to an electrical type of wheel deceleration and acceleration detector device 14. Therefore, when the wheel deceleration or acceleration reaches certain chosen values, these magnetic valves are operated in the manner hereinafter described.

The supply valve 2 consists of a valve housing 15 with two housing parts 16, 17 between which a diaphragm 18 that serves both as the closing and also the activating member, and is composed of an elastic material, is mounted. The diaphragm 18 separates the control

chamber 19 and a valve intake chamber 20 from one another and has a centric attachment 21 which forms a disc valve that is movable into contact with a seat 22 formed on a flange that is integral with a guide bushing 23.

The control chamber 19 can be connected to pipe 7 via housing borings 25, 26, magnetic valve 12, and housing boring 27. The inlet chamber 20 is connected to pipe 7 via the housing boring 25 and a channel 28 serving as a throttle or choke. Thus, the control chamber 19 can be acted on by the pressure in front of or at the inlet of the throttle or choke 28, while the inlet chamber 20 can be acted on by the pressure behind or at the outlet of the throttle.

Diaphragm 18 is supported on its activation or upper side against a roughly conical housing seat 24.

A throttle member 30 with an annular piston 31 and a tubular projection 32 has a sliding fit along guide bushing 23 and is displaceable against a spring 34 in a housing boring 33, the projection 32 being capable of forming a throttle 32, 35 with the housing projection 35.

An annular disc 36 installed in the intake chamber 20, and mounted between the two housing parts 16, 17, has a projection 37 with a funnel-shaped taper in the closing direction, serving as a flow deflecting body, which projection encloses the diaphragm 18 serving as the closing member and is mounted at such a distance from this diaphragm that it turns the flow of air flowing from the housing boring 25 to the housing boring 33 through inlet chamber 20 away from the diaphragm area 38 of diaphragm 18, viewed in the closing direction, thus producing a reduction of pressure which unloads the diaphragm 18 on its lower side thus making it snap acting as it moves in the closing direction.

The projection 21 of the diaphragm 18 is designed as a body of revolution that forms a dished cone with a concavely curved surface 39 serving as a closing area, whose curvature is so selected such that a stream of air flowing from housing boring 25 to housing boring 33 through inlet chamber 20 is turned by this curved surface 39 while a roughly constant effective cross section of flow or one increasing in the closing direction is maintained. The cross section of flow is bordered on one side by the curved surface 39 and on the opposite side by the surface of the flange 22 that is integral with the upper end of the guide bushing 23.

Diaphragm 18 has a metallic reinforcement plate 40 serving to reinforce an unloading spring 41. The spring force of the unloading spring 41 which acts against the elastic force of membrane 18 acting in the opening direction is so dimensioned that when the valve is not activated, the diaphragm 18 maintains a stable open position.

The release valve 3 consists of a valve housing 45 with two housing parts 46, 47, between which a diaphragm 48 is mounted as a closing and activating member. Diaphragm 48 separates a control chamber 49 and an intake chamber 50 from one another and displays a centric projection 51 which forms a disc valve that is movable into contact with a valve seat 52 formed on housing part 47.

The control chamber 49 can be connected with a source of compressed air, such as the reservoir 4, via pipe 6, pipe and corresponding passageway 53, the magnetic valve 13, and a housing boring 54. The intake chamber 50 is connected to the brake cylinder 5 via a

housing boring 55 and pipe 10. An annular disc 56 mounted in the intake chamber 50 is designed and installed in the same manner as annular disc 36 for the intake valve 15. Its funnel-shaped projection 57 encloses the diaphragm 48 serving as the closing member and is installed at such a distance from this diaphragm that it turns a stream of air flowing from housing boring 55 to housing boring or exhaust port 11 through intake chamber 50 away from the front or lower surface of diaphragm 48, viewed in the closing direction, thus producing a reduction of pressure which unloads the diaphragm 48 in the closing direction.

Projection 51 of diaphragm 48 is designed in the same manner as projection 21 of diaphragm 18 and therefore need not be described further. Diaphragm 48 also, like diaphragm 18, has a metallic reinforcement plate 59 serving to reinforce an unloading spring 60 corresponding to spring 41 of the inlet valve 2.

The mode of action of the antiskid device according to FIG. 1 is explained below with reference to the time-pressure curve according to FIG. 2:

When the brake is not activated, the antiskid mechanism is in the position showing FIG. 1 in which the supply valve 2 is open and release valve 3 is closed. Accordingly, control chamber 19 of supply valve 2 is evacuated so that diaphragm 18 is held precisely in the stable open position by its own elastic force due to the counteracting unloading spring 41.

Control chamber 49 of release valve 3 on the other hand, is charged with air via pipe 6, pipe and passageway 53, open magnetic valve 13, and housing boring 54, so that diaphragm 48 is acted on by an activation pressure and its projection 51 serving as a valve disc, is pressed against the valve seat 52 on housing part 47.

If a braking application is initiated by activation of brake valve 9, then the compressed air container 4 is connected to the brake cylinder 5 via pipes 6, 7, housing boring 25, throttle channel or choke 28, inlet chamber 20, housing boring 33, and pipe 8 and in the brake cylinder 5 produces an increasing braking pressure P_B corresponding to the curve $P_{B0} - P_{B1}$ (FIG. 2). Thus a stream of air is produced which flows from a chamber of higher pressure (compressed air container 4) to a chamber of lower pressure (brake cylinder 5) through inlet chamber 20 of the supply valve 2 and is there deflected by the funnel-shaped projection 37 of the annular disc 36 away from the lower surface 38 of the diaphragm 18, the projection 37 thus serving as a flow deflecting body.

This flow of air then carries the air from between the funnel-shaped projection 37 and the lower surface 38 of the diaphragm 18 so that a reduction of pressure dependent on the velocity of flow of the air is produced in this chamber which reduction of pressure has an unloading effect on diaphragm 18 in the closing direction. In this way, the pressure prevailing in inlet chamber 20 is now rendered, to a great degree, inactive with respect to diaphragm 18, so that the latter is unloaded in the closing direction when the compressed air flows through supply valve 2.

The flow of air is subsequently turned by projection 21 of diaphragm 18 in the direction of the valve seat 22 due to the special shape of the surface 39 and reaches boring housing 33, whereby the cross section of flow bordered by the surface 39 and the opposite area of the flange of the guide bushing 23 and increasing in the di-

rection of flow provide an unhindered flow through valve 21, 22.

At the same time, piston 31 of throttle member 30 is acted on on both sides by the pressure of the compressed air flowing so that it remains held by the pressure of the closing spring 34 in the nonthrottling position shown, while braking pressure is built up in brake cylinder 5.

If the rate of wheel deceleration at this time exceeds a certain chosen value which value is an indication that the wheel skid or slip threshold has been reached, the current generated by the detector device 14 in response to this rate of wheel deceleration and supplied to the solenoid coils of the magnetic valves 12 and 13 is reduced to substantially zero. Consequently, the upper valves 61 are unseated and the lower valves 62 are seated by springs 63.

When the lower valve 62 of magnetic valve 13 is thus seated, communication is closed between reservoir 4 and the control chamber 49 of the release valve 3. When the upper valve 61 of magnet valve 13 is thus unseated, fluid under pressure is vented from chamber 49 to atmosphere via bore 54 and past the now open valve 61. Since the brake cylinder 5 is connected to chamber 50 via pipe 10 and bore 55, this fluid under pressure acting in chamber 50 and on the lower side of diaphragm 48 deflects this diaphragm upward so that it is unseated from valve seat 52 against the yielding resistance of spring 60. Fluid under pressure in the brake cylinder 5 now flows to atmosphere via pipes 8 and 10, bore 55, chamber 50, past valve seat 52 and exhaust passageway 11. Thus, the pressure in the brake cylinder 5 is quickly reduced corresponding to the curve $P_{B1} - P_{B2}$ shown in FIG. 2.

It should be noted that when the diaphragm 48 is unseated from the valve seat 52, fluid under pressure present in the bore 33 in supply valve 2 may flow to atmosphere via pipes 8 and 10, bore 55, past valve seat 52 and exhaust passageway 11. This flow of fluid under pressure to atmosphere tends to reduce the pressure in chamber 20 of supply valve 2.

Since valves 61 of magnetic valves 12 and 13 are unseated and valves 62 of these magnet valves are seated simultaneously by the springs 63 when the current in the solenoid coils of these magnet valves is reduced to substantially zero when the wheel begins to skid or slip, the fluid under pressure present in the bore 25 of supply valve 2 will flow to chamber 19 via bore 26, past now open valve 61 of magnetic valve 12, and bore 27.

The supply of fluid under pressure to chamber 19 acts on the upper side of diaphragm 18 and deflects it downward until it contacts valve seat 22 thus quickly cutting off flow of fluid under pressure from the reservoir 4 and brake valve 9 to the brake cylinder 5. This closing of the supply valve 2 takes place in a very short time, since the pressure on the surface 39 on the lower side of diaphragm 18 has been reduced by the flow of fluid under pressure past the funnel-shaped projection 37.

Furthermore, it should be noted that the pressure supplied to the chamber 19 is always higher than that supplied to the chamber 20 via the channel 28 which serves as a throttle or choke. Consequently, this differential of pressure aids in providing for the quick closing of the supply valve 2.

Moreover, the extremely rapid closing of disc valve 21 integral with the diaphragm 18 against the valve seat

22 is also facilitated by the act that this valve has a single moving member (diaphragm 18 and center attachment 21) having a very small mass. Also, it should be noted that as the diaphragm 18 is deflected downward, it is moved away from the conical seat 24 on housing part 16 thereby increasing its effective area that is subject to fluid under pressure in chamber 19. Consequently, the diaphragm 18 is moved downward into contact with valve seat 22 with a snap action.

10 Fluid under pressure is retained in the chamber 20 subsequent to the seating of diaphragm 18 on valve seat 22, it being noted that fluid under pressure is supplied to this chamber 20 from the brake valve 9 via pipe 7, bore 25, and channel 28 which serves as a choke. However, since the release valve 3 is open, fluid under pressure can flow from the bore 33 to atmosphere via pipes 8 and 10, bore 55, chamber 50, past valve seat 52 and exhaust passageway 11. Consequently, the pressure on the lower side of the piston 31 is reduced so that the trapped pressure in chamber 20 and acting on the upper side of this piston 31 moves it and the tubular projection 32 that is integral therewith downward against the yielding resistance of spring 34. As tubular projection 32 is thus moved downward toward housing projection or boss 35, it reduces the cross-sectional area of the passageway through which fluid under pressure may flow to the brake cylinder 5 thereby providing a throttle.

Now let it be assumed that when the pressure in the 30 brake cylinder 5 has been reduced to the value indicated by P_{B2} in FIG. 2, the deceleration of the wheel is above the value that indicates that the skid or slip threshold has been reached. Consequently, the current now generated by the detector device 14 and supplied to the solenoid coil of the magnet valve 13 of release valve 3 is sufficient to cause operation of this valve 13 to seat its upper valve 61 and unseat its lower valve 62. However, this current is not enough to cause operation of the magnet valve 12.

40 This seating of upper valve 61 and unseating of lower valve 62 of magnet valve 13 closes the communication between control chamber 49 and atmosphere and opens a communication between the reservoir 4 and this chamber 49.

45 The supply of fluid under pressure from the reservoir 4 to the control chamber 49 causes rapid downward deflection of diaphragm 48 to the position shown in which it abuts the valve seat 52 thereby closing communication between chamber 50 and atmosphere. This quick closing of the release valve 3 occurs for the same reasons as hereinbefore mentioned in connection with the quick closing of the supply valve 2.

Upon the closing of release valve 3, a residual pressure $P_{B2} = P_{B3}$ is maintained in the brake cylinder 5, while the wheel of the vehicle continues to turn. Thus, by cutting off the flow of fluid under pressure from the brake cylinder 5 to atmosphere at the time wheel deceleration reaches a value above that which indicates that the skid or slip threshold has been reached, the braking force absorption capacity is better utilized at the end of the brake cylinder pressure reduction than would be the case if brake cylinder pressure were reduced to zero.

60 If now the wheel acceleration exceeds a chosen value that indicates that the spinning threshold of the wheel has been reached, the current generated by the detector device 14 and supplied to the solenoid coil of the

magnet valve 12 of supply valve 2 is sufficient to cause operation of this magnet valve 12 to seat its upper valve 61 and unseat its lower valve 62.

This seating of upper valve 61 and unseating of lower valve 62 of magnet valve 12 closes the communication between the reservoir 4 and control chamber 49 and vents the fluid under pressure in this chamber 49 to atmosphere. When control chamber 49 is thus vented, the fluid under pressure present in the chamber 20 is rendered effective to deflect diaphragm 18 upward from seating contact with valve seat 22 to the position shown in FIG. 1 thereby opening a communication between the reservoir 4 and the brake cylinder 5.

This opening of the supply valve 2 results in a resupply of fluid under pressure to the brake cylinder 5 to cause an increase of the pressure therein. However, since piston 31 and tubular projection 32 have been moved downward from the position shown in FIG. 1, in the manner hereinbefore explained, so that projection 32 and boss 35 constitute a throttle or choke, the build-up of pressure in the brake cylinder 5 will occur more slowly, than if piston 31 and projection 32 occupied the position shown in FIG. 1. This slow build-up of brake cylinder pressure better utilizes the braking force absorption capacity of the wheel in that it prevents a reoccurrence of slipping of the wheel.

The supply valve according to FIG. 3 differs from the supply valve according to FIG. 1 only in that its closing member is also unloaded by means of an impingement disc. Parts formed identical to those in FIG. 1 are characterized with reference numbers increased by 100 in comparison to the corresponding numbers in FIG. 1.

Diaphragm 118 displays connecting plug 160 mounted coaxially in an extension of projection 21, carrying on its end protruding into guide sleeve 123 a circular metallic impingement disc 161 connected to it and thus to diaphragm 118 immovably. The diameter of impingement disc 161 is so selected that a flow of air through the guide sleeve 123 and housing boring 133 takes place without throttling.

The impingement disc 161 is so mounted in guide bushing 123 that it extends at a distance from diaphragm 118 so that a stream of air flowing through guide bushing 123 impinges against impingement disc 161, producing an impingement pressure acting on the impingement disc 161, which has an unloading effect, via connecting plug 160, on diaphragm 118 which acts in the closing direction. The distance between the impingement disc 161 and diaphragm 118 is so selected in this case that the impingement pressure produced cannot act directly on the closing area 138 of diaphragm 118.

The mode of operation of the supply valve according to FIG. 3 differs from the mode of operation already described for the supply valve according to FIG. 1 only in that diaphragm 118 is unloaded during the flow of compressed air with the valve open additionally through the flow-dependent impingement pressure produced by the impingement disc 161 so that when magnetic valve 12 is activated to open its valve 61, supply valve 2 is capable of closing even more rapidly.

Naturally, a corresponding impingement disc can be built into release valve 3, since its unloading effect in the closing direction is dependent only on the presence of a flow of air such as also takes place through release valve 3 when the valve is moved to its closed position.

In the examples described, the closing member of the valve is either unloaded by the under pressure produced by a turning body (release valve 3 according to FIG. 1) or by this and the Δp produced by a throttle between the activating pressure and the pressure prevailing in the inlet chamber of the valve (supply valve 2 according to FIG. 1) or finally by both and the impingement pressure (supply valve 103 according to FIG. 3) produced by an impingement body in the closing direction.

Naturally, however, these three flow-dependent unloading possibilities can be used individually or in combination and not only for the supply valve but also for the release valve of the device described.

In view of the extremely short closing times required for antiskid devices, this time is even further shortened in the valves described by the fact that the valves display a diaphragm serving simultaneously as a closing and activating member with a very small mass which is moreover pre-unloaded by a spring.

However, it is possible without difficulty to use the advantages stemming from a flow-dependent unloading of the closing member in the closing direction with respect to the achievement of extremely short closing times also for valves of different design, particularly for pressure-medium or electromagnetically activated disc valves with separate activation organs, especially when during the closing of the valve into the closed position, a flow of pressure medium takes place through it.

In the variant examples described, the valve is closable by moving the closing member against the full pressure of the air stream. The advantages of the flow-dependent unloading of the closing member in the closing direction, however, can be achieved without difficulty in valves which, with respect to the pressure of the air flow, are completely or partially pressure-equalized.

Having now described the invention, what we claim as new and desire to secure by Letters Patent, is:

1. For interposition between an inlet conduit and an outlet conduit, a quick closing valve device controlling flow of fluid under pressure therethrough and comprising:

- a valve seat,
- a movable abutment having a chamber on each side thereof and movable into contact with said seat to cut off flow of fluid under pressure from the inlet conduit to the outlet conduit and out of contact with said seat to provide for flow of fluid under pressure from the inlet conduit to the outlet conduit,
- valve means operative to control the flow of fluid under pressure to a chamber at one side of said abutment and the release of fluid under pressure from said one side to atmosphere, and wherein the improvement comprises:
- flow deflecting means for controlling flow of fluid under pressure from the inlet conduit to a chamber at the other side of said abutment and thence to the outlet conduit in such a manner that the flow of fluid under pressure therethrough causes a reduction of pressure in said chamber at said other side of said abutment to render the fluid under pressure supplied to said chamber at said one side effective to move said abutment with a snap-action movement into contact with said valve seat to cut off

flow of fluid under pressure from the inlet conduit to the outlet conduit.

2. A quick closing valve device, as recited in claim 1, further characterized in that said flow deflecting means comprises a hollow annular truncated cone-shaped member having an outturned flange integral with its larger end and disposed in abutting relationship with the periphery of said movable abutment, said hollow annular truncated cone-shaped member being so disposed as to extend in the direction away from said movable abutment and toward said valve seat whereby said abutment is moved into abutting relationship with the interior of said hollow annular truncated cone-shaped member upon movement into contact with said valve seat.

3. A quick closing valve device, as recited in claim 1, further characterized in that said movable abutment has formed integral therewith on said other side thereof a coaxial concave dished cone with its apex extending in the direction of said valve seat which cone is effective, prior to movement of said abutment into contact with said valve seat, to deflect fluid under pressure in the direction of said seat.

4. A quick closing valve device, as recited in claim 1, further characterized in that said abutment has formed on said other side a stem integral therewith and extending from the center thereof in the direction of said valve seat, and by a member carried adjacent the exterior end of said stem and so disposed as to be subject to fluid under pressure flowing to the outlet conduit which fluid under pressure is effective via said member and said stem to transmit a force to said abutment that

acts in the direction to move said abutment toward said valve seat.

5. A quick closing valve device, as recited in claim 1, further characterized by choke means so disposed on the inlet side of said flow deflecting means that the pressure of the fluid supplied from the inlet conduit to said chamber at said one side of said abutment exceeds the pressure of the fluid supplied from the inlet conduit to said chamber at said other side of said abutment.

10 6. A quick closing valve device, as recited in claim 1, further characterized in that said movable abutment constitutes a valve for cooperation with said seat to control flow of fluid under pressure from the inlet conduit to the outlet conduit.

15 7. A quick closing valve device, as recited in claim 4, further characterized in that said member comprises an annular disc.

8. A quick closing valve device, as recited in claim 7, further characterized in that said abutment comprises 20 a diaphragm constructed of an elastic material.

9. A quick closing valve device, as recited in claim 8, further characterized by a sectionalized casing having a pair of casing sections between which the outer periphery of said diaphragm is clamped, one of said casing sections being provided with an internal conical surface against which one side of said diaphragm normally abuts whereby the effective area of said diaphragm is increased as said one side thereof is moved away from said conical surface in response to the supply of fluid under pressure to said chamber at said one side.
